CLAIM

The ornamental design for a display case for elongated pastry products, as shown and described.

DESCRIPTION

FIG. 1 is a perspective view of a display case for elongated pastry products showing my new design;

FIG. 2 is a front elevational view;

FIG. 3 is a left side elevational view;

FIG. 4 is a right side elevational view, partially broken away to illustrate the shape of the troughs in the base;

FIG. 5 is a rear elevational view;

FIG. 6 is a top plan view thereof; and,

FIG. 7 is a bottom plan view thereof.

FIG. 1

FIG. 2

FIG. 3

FIG. 4

FIG. 5

FIG. 6

FIG. 7
